UNITED STATES PATENT OFFICE.

WILLIAM W. SLOANE, OF CHICAGO, ILLINOIS, ASSIGNEE TO GOODMAN MANUFACTURING COMPANY, OF CHICAGO, ILLINOIS, A CORPORATION OF ILLINOIS.

EXPLOSIONPROOF FUSE.

Application filed July 10, 1920, Serial No. 395,322. Renewed November 6, 1924.

This invention relates to improvements in explosion-proof electrical fuses or cutouts, and has for its principal object to provide a safety fuse for use in gaseous mines, or under similar conditions in which explosions may be caused by the arcing of exposed fuse connections.

To this end, I provide an improved construction comprising a renewable fuse element and a casing therefor on which the fuse is enclosed in the casing, and cannot be removed therefrom without first breaking the electric circuit.

The further object of this invention is to provide a construction in which it is practically impossible to insert a substitute for the fuse element between the fuse connections, thereby affording a protection against exposed fuse connections.

Further objects will appear from the following description, reference being had to the accompanying drawings, in which Figure 1 is a vertical cross-section of my improved device, showing the fuse element in locked position in the casing.

Figure 2 is a transverse cross-section taken on line 2—2 of Figure 1, showing the connecting wires in place.

Figure 3 is a cross-section taken on line 3—3 of Figure 1.

Figure 4 is a perspective view of the device.

Figures 5 and 6 are details.

Referring now to details of my construction, my device comprises two main elements, namely; an outer casing 1 and a removable fuse holder 2, adapted to hold a standard fuse element 20, and to be inserted in the casing 1 and locked therein, so as to provide a practically air-tight enclosure for the fuse. The outer casing 1 comprises a cylindrical body 3 preferably of metal mounted on a base 4, having extending lugs 5, 5 for mounting the device in any suitable manner. The inner portion of the casing 3 is insulated by suitable means such as an annular insulation ring 8, and an insulation disk 9 adjacent the base 4. A second insulation disk 10 abuts the insulating ring 8 and is removed from the disk 9 so as to form a compartment therebetween, indicated at 11. The disk 10 carries a pair of fuse clips 12, 12 extending inwardly and enclosed in the compartment 11. An auxiliary insulating disk 13 may be super-imposed on the

disk 10, and all of the insulating pieces just described are retained in place by an annular metallic ring 14 threaded into the casing 3, as shown in Figure 1. A pin 15 in the casing is adapted to register with a suitable notch 16 on the edge of the insulation plate 10 to properly position the latter in the casing.

The fuse holding element 2 comprises a cylindrical plug member 17, adapted to fit tightly in the cylinder body 3, and having a long bearing surface therein, so as to provide an "explosion-proof" joint, thru which any flame from an arc, or an explosion caused thereby, in the casing, cannot reach the outer air. Said holding element is provided with a handle 17^a. Locking flanges 18, 18 extend laterally from the outer end of the plug member 17, and are adapted for locking engagement with the lips 19, 19 on the casing.

A fuse element 20 is clamped to the holding element 2 by means of a holder piece 21 extending inwardly from the plug member 17, and forming a holding piece for the fuse 20, and a clip, or band 22, preferably attached at each end to the plug member 17 and passing around the holding piece 21 and the fuse 20 to hold both in place.

The fuse 20 may be of the usual "cartridge" type having either a "renewable link," or an ordinary destructible link, as desired. Such fuses usually have metallic end pieces 23, 23, and a central body portion 23^a of non-conducting material which forms a casing for the enclosed fusible element. The holding piece 21 is preferably made of insulating material and has an end face shaped to receive the fuse casing, as shown.

The fuse terminals 12, 12 are connected to the outside circuit by means of terminal wires 26 and 27, which pass thru openings 28, 28, respectively, in the side walls of the casing adjacent their respective terminal clips, and thence thru recesses 30 and 31. Said recesses are adapted to receive sealing substance of any suitable material so as to afford an air-tight connection for the conductor wires. From the recesses 30 and 31, the wires pass into an enlarged recess 32, where they are adapted to be spliced in any suitable manner with conductors 33 and 34 from the outside circuit, as indicated in Figure 2. I also provide a suitable cap 35 which covers the recess 32. In case the conductors 33 and 34 are enclosed in a conduit 36, I

provide a holder 37 for the conduit on the cap 35 thru which the conduit 36 extends, and is secured to said cap by a removable clip 38. It will be understood, however, that any other suitable arrangement for connecting the conductor wires 26 and 27 with the outside circuit may be employed, if desired.

It will be observed that the clips 12, 12^a are similar to each other in construction, but face in opposite directions to each other, so as to receive the end of fuse element 20 when the latter is rotated into contacting engagement therebetween as will hereinafter be described. A preferable method of connecting the conductor wires to their respective clips 12, 12 is by inserting the bare end of one of the wires 26, 26 thru a suitable groove 39 cut in the lower face of the clip 12, so as to pass thereunder and be secured on a binding post 12^a at the opposite end thereof. The other conductor wire 27 is secured directly to the binding post 12^b.

Figure 5 shows the shape of the insulating plate 10 which forms the partition of the inner compartment 11. This plate is provided with an elongated aperture 24 so proportioned as to allow the fuse 20 to pass therethru, but arranged at right angles to the normal position of the fuse when the ends 23, 23, thereof, are engaged in the fuse clips 12, 12. The plate 13 is also provided with a similarly shaped aperture 25.

The operation of the device is as follows: The fuse and fuse holder may be inserted in the casing so that the fuse 20 passes thru apertures 24 and 25, and the locking flanges 18, 18, are out of engagement with the retaining lips 19, 19. The holding element 2 is then rotated in the casing by means of the handle 40 so that the ends 23, 23 of the fuse element are brought into engagement with the retaining clips 12, 12. By the same movement, the locking flanges 18, 18 become locked, and provide a practically airtight compartment for the fuse. It will be clear that in order to unlock the fuse holder from the casing, it is necessary to reverse the above described action by rotating the holder so as to move the ends 23, 23 of the fuse element out of engagement with the retaining clips 12, 12 before the locking flanges 18, 18 can be unlocked and the fuse element withdrawn from the casing.

A further feature of my invention is a construction which makes it practically impossible for a careless operator to insert a substitute for the fuse element so as to close the circuit within the casing while the casing is unlocked. It is well known to those familiar with the operation of safety devices of this character, that in spite of all warnings as to the danger of overloading a circuit, and of explosions caused by open fuse contacts, yet a large proportion of op-

erators will ignore all provisions for their own welfare by attempting to contrive some method of defeating the purpose of the safety device. One of the common practices is to connect the ordinary fuse terminals with fuse wire, and in fact common wire, and many other articles are used for this purpose. It will be seen, however, that with my improved construction, it is practically impossible to reach the retaining clips 12, 12^a for the purpose of connecting these terminals with any substitute for the fuse element in the manner above suggested. While it may be possible to insert fuse wire or other substitute for the cartridge 20, yet when this is done, the cartridge must be clamped in the fuse holder 2, and the entire element inserted in the casing before proper contact of the fuse device can be made. Therefore, my device affords a protection against exposed fuse connections.

Having described my invention what I claim as new and desire to cover by Letters Patent, is:

1. In combination with a fuse member of the cartridge type, a casing having an opening, a pair of contacts for said fuse member in said casing, a partition intermediate said opening and said contacts having a restricted aperture affording a passageway for said fuse member in a position removed from engagement with said contacts, and a holding element having a portion thereof adapted to form a closure for said opening, and a second portion adapted to detachably secure the fuse member intermediate its ends, and to project said fuse member thru said restricted aperture, whereby said fuse member may be moved into and out of engagement with said contacts when said holding element is in closed position in the casing.

2. In combination with a fuse member of the cartridge type, a casing having an opening, a pair of contacts for said fuse member in said casing, a partition intermediate said opening and said contacts having a restricted aperture affording a passageway for said fuse member in a position removed from engagement with said contacts, and a holding element having a portion thereof adapted to form a closure for said opening, and a second portion adapted to detachably secure the fuse member intermediate its ends, and to project said fuse member thru said restricted aperture, whereby said fuse member may be moved into and out of engagement with said contacts when said holding element is in closed position in the casing, and means independent of said contacts for locking the said holding element in the casing in all positions of engagement between said fuse element and said contacts.

3. In combination with a fuse member of the cartridge type, a casing having a cylindrical opening, a pair of contacts for said

- fuse member in said casing, a partition intermediate said opening and said contacts having a restricted aperture affording a passageway for said fuse member in a position removed from engagement with said contacts, and a removable element having a portion thereof adapted to rotate in said opening and to form a closure therefor, and a second portion adapted to detachably secure the fuse member intermediate its ends, and to project said fuse member thru said restricted aperture, whereby said fuse member may be moved into and out of engagement with said contacts when said removable element is in closed position in the casing.
4. In combination with a fuse member of the cartridge type, a casing having a cylindrical opening, a pair of contacts for said fuse member in said casing, a partition intermediate said opening and said contacts having a restricted aperture affording a passageway for said fuse member in a position removed from engagement with said contacts, a removable element having a portion thereof adapted to rotate in said opening and to form a closure therefor, and a second portion adapted to detachably secure the fuse member intermediate its ends, and to project said fuse member thru said restricted aperture, whereby said fuse member may be moved into and out of engagement with said contacts when said removable element is in closed position in the casing, and means independent of said contacts for locking said holding element in the casing in all positions of engagement between said fuse element and said contacts.
5. In a device of the class described, a casing having an opening, an elongated fuse member, a fuse holding element adapted for rotation in said casing, and having a portion thereof adapted to hold said fuse member intermediate its ends with its longer axis at an angle to the axis of rotation of said holding element, electrical contacts in said casing for the ends of said fuse member, and a partition intermediate said opening and said contacts having a restricted aperture therethru affording a passageway for said fuse member in a position removed from said contacts.
6. In a device of the class described, a casing having an opening, an elongated fuse member, a fuse holding element adapted for rotation in said casing, and having a portion thereof adapted to hold said fuse member intermediate its ends with its longer axis at an angle to the axis of rotation of said holding element, electrical contacts in said casing for said fuse member, a partition intermediate said opening and said contacts having a restricted aperture therethru affording a passageway for said fuse member in a position removed from said contacts, and means independent of said contacts for locking said holding member in the casing in all positions of engagement between said fuse member and said contacts.
7. In combination with a fuse member of the cartridge type, a casing, an insulating partition fixed in said casing and forming a compartment therein, a pair of contacts for said fuse member mounted on said partition and spaced from each other within said compartment, said partition having an elongated slot adapted to afford passage of said fuse member in a position removed from said contacts, a holding element for said fuse member, adapted to form a closure for the casing opening and locking means independent of said contacts adapted to lock said holding member against longitudinal movement while said fuse member is engaged with said contacts.
8. In combination with a fuse member of the cartridge type, a casing, an insulating partition fixed in said casing and forming a compartment therein, a pair of spring clips each adapted to receive an end of said fuse member and opening in directions opposite to each other, said clips being mounted on said partition and spaced from each other within said compartment, said partition having an elongated slot adapted to afford passage of said fuse member in a position removed from said clips, and a removable circular fuse holding member having a portion thereof adapted to hold a fuse element intermediate the ends of the latter, said holding member being adapted for rotation in said casing to form a closure therefor, whereby said fuse member may be moved into and out of engagement in said spring clips.

Signed at Chicago, this 7th day of July,
A. D. 1920.
